DESIGN FOR AN ILLUMINATED DISPLAY STAND FOR BOTTLES

Adolph Berman, New York, N. Y.

Application March 30, 1936, Serial No. 61,861

Term of patent 3½ years

To all whom it may concern:

Be it known that I, Adolph Berman, a citizen of the United States, residing in the city, county, and State of New York, have invented a new, original, and ornamental Design for an Illuminated Display Stand for Bottles, of which the following is a specification, reference being had to the accompanying drawing, forming part thereof.

The drawing shows a perspective view of an illuminated display stand for bottles showing my

design. This view shows a plurality of concentric semi-circular sections of decreasing diameter toward the upper elevation. The two lowermost sections are subdivided to provide individual platforms for bottles. The upright semi-circular walls have translucent windows.

I claim:

The ornamental design for an illuminated display stand for bottles, as shown and described.

ADOLPH BERMAN.
